United States Patent Office

Des. 202,667
Patented Oct. 26, 1965

202,667

PHOTOGRAPHIC CAMERA

David E. Hansen, Fairport, N.Y., assignor to Eastman Kodak Company, Rochester, N.Y., a corporation of New Jersey

Filed Dec. 23, 1963, Ser. No. 77,902

Term of patent 14 years

(Cl. D61—1)

FIG. 2

FIG. 4

FIG. 1

FIG. 5

FIG. 3

FIG. 6

FIG. 9

FIG. 7

FIG. 10

FIG. 8

FIG. 1 is a front elevational view of a photographic camera, showing my new design;

FIG. 2 is a top plan view thereof;

FIG. 3 is the rear view thereof;

FIG. 4 is a left-side elevational view thereof;

FIG. 5 is a right-side elevational view thereof;

FIG. 6 is a bottom plan view thereof;

FIG. 7 is a view similar to FIG. 1 but showing the flash holder extended;

FIG. 8 is a rear elevational view thereof;

FIG. 9 is a left-side elevational view thereof; and

FIG. 10 is a right-side elevational view thereof.

The broken-line showing of a flash lamp in FIG. 7 is for illustrative purposes only.

I claim:

The ornamental design for a photographic camera, as shown and described.
